UNITED STATES PATENT OFFICE.

JOHN HENRY MARSH, OF LONDON, ENGLAND.

SASH-FASTENER.

973,285.

Specification of Letters Patent. Patented Oct. 18, 1910.

Application filed June 25, 1910. Serial No. 568,866.

To all whom it may concern:

Be it known that I, JOHN HENRY MARSH, a subject of the King of Great Britain, and resident of 195 Markhouse road, Waltham-
5 stow, London, England, engineer, have invented certain new and useful Improvements in Sash-Fasteners, of which the following is a specification.

This invention relates to holders for windows with sliding sashes especially house, railway carriage, motor and carriage windows of the type in which a spring-pressed plunger having a roller on one member of the window is adapted to engage the other 10 member of the window and to be locked in position, and has for its object to provide an improved construction of such holders. The window has on the edge of the sliding part a corrugated strip of metal, while the 15 frame is provided with a spring-pressed plunger adapted to coact therewith. The plunger is adapted to slide in a guide frame within which a coiled spring or rubber buffer is disposed. The outer end of the 20 plunger is provided with a roller and the inner end is beveled for a purpose to be hereinafter set forth.

In accordance with this invention a sliding member is arranged in the frame of 25 the window and transversely of the plunger, said sliding member having an aperture through which said plunger can slide and having an inclined part adjacent to said aperture and adapted to coact with the beveled end of the plunger, so that when the member is slid the end of the plunger rides up the incline and the outer end of the plunger is held in engagement with the corrugated strip on the sliding part of the 30 window in such manner as to prevent the plunger being forced back and consequently to prevent the window from being moved. Preferably each sliding part of the window is provided with two holders, one on each 35 side.

Referring to the accompanying drawings, Figure 1 is a sectional elevation showing one form of window holder constructed in accordance with this invention as applied to 40 the lower sliding sash of a window. Fig. 2 is a face view of a detail. Fig. 3 is an elevation at right angles to the view shown in Fig. 2. Fig. 4 is a fragmentary face view in the direction of the arrow A, Fig. 1 and Fig. 5 is a section on line 5—5 of Fig. 1. 45

a is a strip of corrugated metal secured

to the edge of the lower sliding sash b of the window.

c is a plunger mounted in a frame d and provided at its outer end with a roller e 60 pivoted on a pin f between lugs g g on said plunger.

h is a coiled spring disposed within the frame d and adapted to press on a shoulder j on the plunger c. A corresponding spring-pressed plunger is arranged behind the above-mentioned plunger in the plane of the upper sliding sash of the window. 65

k is a member arranged to be slid transversely of the plungers in a frame m and provided with apertures n through which said plungers can slide. Adjacent to each aperture n is an inclined part o adapted to coact with the beveled end p of the plunger c when the member k is slid and for 70 this purpose the member k is provided with a neck q passing through a plate r secured to the frame s of the window and with a knob t. 75

In use as the sash b is slid the corrugated strip a rides over the roller e on the plunger c and causes said plunger to be moved against the action of its spring h, the end of the plunger passing through the aperture n in the member k. As will be seen 80 the sash b will be retained at any desired height by the coacting plunger and corrugated strip. When it is desired to prevent the window from being moved the member k is slid so that the aperture n and the 85 plunger c are out of register, as shown in Fig. 4, so that the incline o coacting with the beveled end p of the plunger c causes the roller e to be pressed against the corrugated strip a and prevents the window from 90 being moved since the plunger c cannot be forced back to allow the corrugations to pass. 95

If desired a rubber buffer may be substituted for the coiled spring h. The configuration of the corrugated strip a and the 100 stroke of the plunger c will depend on the weight of the window to be supported.

By the use of such window holders the grip on the sliding sashes prevents the 105 windows from rattling.

Claim:

A sash fastener, comprising a corrugated strip adapted to be secured to a sash, a casting adapted to be secured to a window frame, a spring pressed plunger in the casting and having its outer end beveled and projecting through an aperture in the cas- 110

ing, a roller mounted on the inner end of the plunger, a keeper frame secured to the outer end of the casing, and a bar mounted entirely within the window frame to slide 5 transversely to the plunger and having an aperture through which the beveled end of the plunger is adapted to project, said bar

being provided on its inner face with an inclined surface leading to the aperture thereof.

JOHN HENRY MARSH.
